UNITED STATES PATENT OFFICE.

ALEXANDER FENTON, OF SURREY, ENGLAND.

DESIGN FOR A COMBINED HEEL AND SOLE.

Application filed January 5, 1923. Serial No. 4,821. Term of patent 3½ years.

To all whom it may concern:

Be it known that I, ALEXANDER FENTON, a subject of the King of Great Britain, residing at Surrey, England, have invented a new, original, and ornamental Design for a Combined Heel and Sole, of which the following is a specification, reference being had to the accompanying drawing, forming part thereof.

In the drawing:

The figure is a bottom plan view of the combined sole and heel, showing my new design.

I claim.

The ornamental design for a combined heel and sole as shown.

ALEXANDER FENTON.

Witnesses:

F. E. SQUIRE,
B. CLARK.
